SAFETY DEVICE FOR SWITCHES

Filed April 12, 1926

William G. Hartwig

Inventor:

By Robert H. Brown, M.A.
See p. 15.

UNITED STATES PATENT OFFICE

WILLIAM G. HARTWIG, OF CHICAGO, ILLINOIS, ASSIGNOR TO RAILWAY UTILITY COMPANY, OF CHICAGO, ILLINOIS, A CORPORATION OF ILLINOIS

SAFETY DEVICE FOR SWITCHES

Application filed April 12, 1926. Serial No. 101,487.

My invention relates to that type of switch used for controlling currents of some magnitude, as for example, for motor-driven machines, in which the switch proper is enclosed in a casing and there is provided a socket and plug for conveniently connecting the switch in the circuit in which it is employed and disconnecting it therefrom. In devices of this character, as is well-known, serious results may follow and frequently have resulted from the pulling or insertion of the plug while the switch is in the closed position. Prior to my invention means has been devised for so interlocking the switch and the plug that the latter cannot be withdrawn except when the switch is in the open position. My invention relates to an improvement in means of this character and has for its object to provide a simple and reliable construction adapted to switches of this general character, notwithstanding specific differences therein and which may be readily incorporated in such constructions at a minimum of expense. I have described herein and shown in the accompanying drawings a preferred form of my invention as applied to such a switch of known type. It is to be understood, however, that the specific disclosure is for the purpose of exemplification only and that the scope of the invention is defined in the following claims in which I have endeavored to distinguish it from the prior art so far as known to me without, however, relinquishing or abandoning any portion or feature thereof.

In the drawings accompanying and forming a part of this specification, Fig. 1 is a vertical section through the center of such a switch to which my invention has been applied, and Fig. 2 a plan view partly in section of so much thereof as will aid in understanding the nature of my improvement.

In the embodiment of the invention shown in the drawing, the switch proper and its enclosing casing are of known construction, the casing comprising a main casting 3 within which the base 4 for the switch is mounted, and a cover plate 5 in which is journaled the hand operated means 6 for throwing the switch.

In the form of switch chosen for illustra-

tion of the invention there are two pairs of stationary contacts 7, 8 with which cooperate the pivoted oscillating contact or bridging members 9—9.

The movable contacts are each carried between a pair of insulating blocks 10 and 11 mounted on a stub 12 which is journaled at 13 in one of the sides of the U-shaped bracket 14. A U-shaped yoke 15 is secured to the two shafts 12 and the pairs of insulating blocks 10 and 11 so as to form therewith a movable contact member. A bell crank lever 16 is pivoted at 17 between the side pieces 14^a of the U-shaped bracket, and the arm 16^a of said lever is perforated to receive a rod or pin 18 which, at its other end, extends through a hole 19 in the cross-member 15^a of the pivoted yoke 15. A spring 20 surrounds said pin or rod and is compressed between the arm 16^a of the lever 16 and the cross-member 15^a of the pivoted yoke. The pivoted yoke is limited in its clockwise movement (as seen in Fig. 1) by engaging the edge 21 of the U-shaped bracket and its movement in the other direction is arrested by contact with the edge 22 of said U-shaped bracket. The arm 16^b of the bell crank lever 16 may be swung from the full line position shown in Fig. 1 to the dotted line position, by the hand operated device 6. Manifestly with the parts in the full line position of Fig. 1, the closed position of the switch, the pressure of the spring 20 holds the yoke 15 in contact with the stop surfaces 21. When the bell crank lever 16 is swung towards the dotted line position and after the spring 20 is carried past the pivotal point 12 of the yoke 15, the pressure of the spring throws the yoke to the dotted line position, the open position of the switch.

At 23 are shown insulating shields. As heretofore stated the switch per se is old and is not claimed herein except in combination with the interlocking device herein-after described. The switch box is provided with a sleeve or socket 25 for the insertion of the plug 26. The plug and socket are per se old. The plug is provided as usual with the terminals 27 which enter the fixed terminals 28 of the socket, said terminals being properly insulated by the insulating blocks 29—30 re-

spectively. The terminals 28 may be connected to the switch in the usual manner.

As heretofore stated, the plug and socket per se as well as the switch and housing are old, and are not claimed herein except in connection with the inter-locking device to be now described.

The socket is formed with a longitudinal recess or channel 31, and the inner face of the socket with a cross channel 32. A latch 33 is formed with trunnions 34 which trunnions, when the device is assembled, rest loosely within the transverse channel 32. The left hand end of the latch, as seen in Fig. 1 is offset or hooked as at 36 to enter a notch or perforation 37 in the shell of the plug. The other arm 38 of the latch is so bent that when it is engaged by the operating member or yoke 15 of the switch it is thrown into the full line position in which the hook 36 enters the opening 37 in the plug shell. Thus when the switch is in the closed position shown the plug can neither be inserted in nor withdrawn from the socket, being prevented therefrom by the latch. When, however, the switch is in the open position shown in dotted lines in Fig. 1, the latch is free to move back into the channel or groove in the interior of the socket. A spring plate 40 is formed with a finger 41 which extends over the top of the latch and tends to restore the latter to the dotted line position. The spring plate is screwed to the face of the socket at 42 and extends over the cross-channel 32 at 43, thus serving also to retain the trunnions of the latch in position in the cross-channel.

The switch is operated and the plug inserted and withdrawn in the usual manner, but when the switch is in closed position, the plug can neither be inserted nor withdrawn thus preventing and eliminating danger of fire and injury which otherwise might result from the closing or opening of the circuit by the insertion or withdrawal of the plug. Manifestly when the switch is in the closed position shown, the pivoted latch is held immovably in the full line position. If the plug is already in place, it cannot be withdrawn. Or if it be attempted to insert the plug, the end of the latter will engage the lug on the latch and be prevented from being inserted to close the circuit. When, however, the switch is in the open, or dotted line position, the spring retracts the latch to the dotted line position and the plug may be freely inserted or withdrawn.

I claim:

In a device of the class described, a casing having a switch therein, said switch comprising a member movable from open to closed position, a plug socket on the casing having a longitudinal groove and having a transverse groove upon its inner face, a latch having trunnions in said transverse groove and the engaging end of which latch extends into

said longitudinal groove in the socket, said latch also extending into the path of movement of the movable member of the switch and locked by the latter in plug engaging position when the switch is closed, and a spring plate extending over the transverse groove and holding the trunnions of the latch therein and comprising also a spring finger tending to press the latch into non-engaging position.

In testimony whereof, I have subscribed my name.

WILLIAM G. HARTWIG.
